THREAD GUIDE

Michael J. McHale, Scranton, Pa.

Application August 7, 1936, Serial No. 94,861

10 Claims. (Cl. 242—157)

My invention relates to thread guides for winding machines and more particularly to means for attaching a guide eye to a tension or other support arm.

5 In Patents 1,965,044 and 2,023,179 dated July 3, 1934, and December 3, 1935, respectively, I have disclosed a thread guide fastening means in combination with a faller arm structure, wherein in the guide may be easily and quickly replaced 10 without the use of any special tool. The present invention is an improvement over the arrangements disclosed in the above referred to patents and relates to an improved thread guide structure of general application with winding 15 machines and various attachments used therewith.

An object of my invention is to provide a fastening means for thread guides whereby the guide eye may be readily attached or detached 20 from its supporting arm or bracket.

Another object of my invention is to provide an improved locking means for the guide whereby the guide is held in tight engagement with the support.

25 Still another object of my invention is to provide an improved thread guide and holder therefor wherein the guide may be easily and quickly attached to its holder without the use of any special tool.

30 Yet another object of my invention is to provide an improved thread guide and fastening means therefor, whereby the angular position of the guide with respect to its holder, may be changed when it is desired to vary the thread 35 tension.

A still further object of my invention is to provide an improved thread guide eye adapted to be used in combination with various types of winding machine structures and attachments used 40 therewith.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

45 In order to make my invention more clearly understood, I have shown in the accompanying drawing means for carrying the same into practical effect, without limiting the improvements 50 in their useful applications to the particular con-

structions, which for the purpose of explanation, have been made the subject of illustration.

In the drawing:

Figure 1 is a side elevational view, partly in section, showing a thread guide and support. 5

Fig. 2 is a plan view of the arrangement shown in Figure 1.

Fig. 3 is a side elevational view of a thread guide support and guide attaching means.

Fig. 4 is an end view of the base of the guide 10 shown in Fig. 2.

Fig. 5 is a side elevational view of a modified form of thread guide support.

Fig. 6 is a side elevational view, partly in section, showing a modified form of thread guide 15 used with the support shown in Fig. 5; and

Fig. 7 is an end view of the base of the guide shown in Fig. 6.

Referring to the drawing and more particularly to Figures 1 and 2 thereof, there is shown a support arm 1 having a thread guide, designated generally by numeral 2, associated therewith. The support arm is provided with a threaded portion 3 and a flat end portion 4 adapted to seat in a recess formed in the guide. The guide member 2 is formed with a thread receiving portion 5, a tapered body portion 6 having a recess 7 extending longitudinally thereof and grooves 8 and 9 terminating in recesses 10 and 11. The body portion of the guide is also provided with a groove 12 extending across the end thereof, as more clearly shown in Fig. 4.

Referring to Fig. 3, the flat end 4 of the support arm is provided with an aperture 13, through which is threaded a looped member designated 35 generally by numeral 14. The loop member comprises a base portion 16 and arm members 17 and 18 extending outwardly therefrom. Loop member 14 may be formed of any suitable material; however, it is preferably made of steel wire having 40 sufficient tension to normally maintain the arms in their predetermined separated position. The diameter of opening 13 formed in flat portion 4 of the support arm is substantially the same as the diameter of the wire forming the loop member, so that the loop will be frictionally maintained in a position substantially parallel with the axis of the support arm. It will be noted 45 that the arms of the loop member are inclined outwardly and the free ends terminate in hook members 19 and 20 which members are adapted to seat in recesses 10 and 11 formed in the base portion of the guide.

In order to mount a thread guide on the support, the end of the tapered base portion is in- 55

serted between arms 17 and 18, with the hook members seated in grooves 8 and 9 formed on opposite sides of the base of the guide; the guide is then pushed forwardly until the flat end portion 4 is fully seated in recess 7 formed in the base of the guide. When the flat end portion is fully seated, arms 17 and 18 rest in grooves 8 and 9, hook members 19 and 20 are seated in recesses 10 and 11 and vertical portion 16 of the loop member is seated in groove 12 formed across the end of the base of the guide. By means of this arrangement, the guide is readily and easily placed upon its support and held in the operative position by means of the loop. The longitudinal 10 recess formed in the base of the guide is preferably of substantially the same cross section as the flattened portion 4 of the support arm so that a snug seat is provided when the flat portion is seated in the recess.

Referring to Figs. 5 and 6 there is shown a modified form of thread guide and support therefor, wherein the angular position of the guide with respect to its support may be adjusted so that the tension on the thread can be varied. It 20 will be noted in this arrangement that support member 1 is provided with a cylindrical end portion 21 and an intermediate flat portion 4' between the plain cylindrical end 21 and threaded portion 3 of the support. The thread guide is 25 of substantially the same configuration as the guide used in connection with support member shown in Figure 1; however, it differs therefrom in that the recess 22 formed longitudinally of the base of the guide is cylindrically shaped and 30 adapted to receive the cylindrical end 21 of the support member. The guide is further provided with a cylindrical shaped base having a plurality of grooves 23 formed exteriorly thereof and corresponding diametrically opposite grooves 12' 35 across the end of the base portion, grooves 12' being adapted to receive section 16 of the loop when the guide member is mounted upon its support.

It will be appreciated that the transverse or 40 diametrically opposite grooves 12' may be eliminated, since the guide can be supported and held in the operative position on the support member by means of the engagement of the arms 17 and 18 of the loop with grooves 23 in which 45 they are adapted to seat. By means of this arrangement, the angular position of the thread guide may be changed so as to vary the tension on the thread. As in the arrangement shown in Figure 1, the guide is placed in the operative position by inserting it on the support member with the plain cylindrical end 21 in recess 22 formed in the base of the guide and permitting arms 17 50 and 18 to seat in a pair of grooves 23, ends 19 and 20 of the loop member being seated in recesses 10 and 11 formed at the ends of the grooves. In order to vary the tension on the thread, the position of the guide with respect to support member 3 is varied by rotating it so that a different pair of grooves 23 are brought into position to receive the arms of the loop member.

While I have shown and described the preferred embodiment of my invention, I wish it to be understood that I do not confine myself to the precise details of construction herein set forth, by way of illustrations, as it is apparent that many changes and variations may be made therein, by those skilled in the art, without departing from the spirit of the invention, or exceeding the scope of the appended claims.

What I claim is:

1. In a thread guide device for winding machines, the combination of a support arm having a support engaging portion and a free end adapted to receive a guide eye, a looped member attached to the support arm in proximity to its free end, comprising a base portion and two arms extending outwardly therefrom terminating in free ends, the arms and base portion being co-planar, a guide eye attached to the support arm comprising a base portion and a thread receiving portion, a recess longitudinally of the base portion forming a seat for the free end of the arm and grooves in the body portion to receive the arms of the loop. 15

2. In a thread guide device for winding machines, the combination of a support arm having a support engaging portion and a free end adapted to receive a guide eye, a looped member attached to the support in proximity to its free end, comprising a base portion and two arms extending outwardly therefrom terminating in free ends, the arms and base portion of said looped member being co-planar, a guide eye attached to the support arm comprising a base portion and a thread receiving portion, the base portion of the guide being tapered and provided with grooves on opposite sides thereof to receive the arms of the loop and a recess longitudinally of the base portion forming a seat for the free end 20 of the arm. 25

3. In a thread guide device for winding machines, the combination of a support arm having a support engaging portion and a free end adapted to receive a guide eye, a looped member attached to the support arm in proximity to its free end comprising a base portion and two co-planar arms extending outwardly therefrom terminating in free ends, the ends of said arms being bent inwardly to form hook members, a guide eye attached to the support arm comprising a base portion and a thread receiving portion, a recess longitudinally of the base portion forming a seat for the free end of the arm and grooves in the body portion of the guide on opposite sides thereof to 45 receive the arms of the loop, each groove terminating in a recess at its end near the thread receiving portion of the guide to receive the hook members formed in the ends of the loop. 35

4. In a thread guide device for winding machines, the combination of a support arm having a support engaging portion and a free end adapted to receive a guide eye, a looped member attached to the support arm in proximity to its free end, comprising a base portion and two arms extending outwardly therefrom terminating in free ends, the arms and base portion being co-planar, a guide eye attached to the support arm comprising a base portion and a thread receiving portion, a recess longitudinally of the base portion forming a seat for the free end of the arm, a groove 50 extending across the end of the base of the guide to receive the base portion of the loop and grooves in the body portion of the guide to receive the arms of said loop. 55

5. In a thread guide device for winding machines, the combination of a support arm having a threaded support engaging portion and a flat free end adapted to receive a guide eye, a looped member threaded through an aperture formed 70 in the flat end of the support arm, comprising a base portion and two arms extending outwardly therefrom terminating in free ends, the arms and base portion of the looped member being co-planar, a guide eye attached to the support arm 75

- comprising a base portion and a thread receiving portion, a recess longitudinally of the base portion forming a seat for the flat portion of the support arm, a groove extending across the end 5 of the base of the guide to receive the base portion of the loop and grooves in opposite sides of the body portion to receive the arms of said loop.
6. In a thread guide device for winding machines, the combination of a support arm having 10 a support engaging portion and a free end adapted to receive a guide eye, a looped member attached to the support arm in proximity to its free end, comprising a base portion and two co-planar arms extending outwardly therefrom terminating in free ends, the ends of said arms being bent inwardly to form hook members, a guide eye attached to the support arm comprising a base portion and a thread receiving portion, a recess longitudinally of the base portion forming 15 a seat for the free end of the arm, grooves in the body portion of the guide on opposite sides thereof to receive the arms of the loop, each groove terminating in a recess at its end near the thread receiving portion of the guide to receive the hook members formed in the ends of the loop and a groove extending across the end of the base of the guide to receive the base portion of said loop.
7. In a thread guide device for winding machines, the combination of a support arm having 20 a threaded support engaging portion and a flat free end adapted to receive a guide eye, a looped member threaded through an aperture formed in the flat end of the support arm, comprising a base portion and two co-planar arms extending 25 outwardly therefrom terminating in free ends, the ends of said arms being bent inwardly to form hook members, a guide eye attached to the support arm comprising a base portion and a thread receiving portion, a recess longitudinally of the base portion forming a seat for the free end of the arm and a plurality of diametrically opposite grooves in the body portion of the guide to receive the arms of 30 the loop.
8. In a thread guide device for winding machines, the combination of a support arm having a threaded support engaging portion and a flat free end adapted to receive a guide eye, a looped member threaded through an aperture formed in the flat end of the support arm, comprising a base portion and two co-planar arms extending 35 40 45 50 outwardly therefrom terminating in free ends, said arms being bent inwardly to form hook members, a guide eye attached to the support arm comprising a base portion and a thread receiving portion, a cylindrically shaped recess longitudinally of the base portion forming a seat for the free end of the arm and a plurality of diametrically opposite grooves in the body portion of the guide to receive the arms of the loop, each groove terminating in a recess at its end near the thread receiving portion of the guide to receive the hook members formed in the ends of the loop.
9. In a thread guide device for winding machines, the combination of a support arm having a threaded support engaging portion and a cylindrically shaped unthreaded free end adapted to receive a guide eye, a looped member threaded through an aperture formed in the unthreaded portion of the support arm, comprising a base portion and two arms extending outwardly therefrom terminating in free ends, the arms and base portion being co-planar, a guide eye attached to the support arm comprising a base portion and a thread receiving portion, a cylindrically shaped recess longitudinally of the base portion forming a seat for the free end of the arm and a plurality of diametrically opposite grooves in the body portion of the guide to receive the arms of the loop.
10. In a thread guide device for winding machines, the combination of a support arm having a threaded support engaging portion and a cylindrically shaped unthreaded free end adapted to receive a guide eye, a looped member threaded through an aperture formed in proximity to the end of the support arm comprising a base portion and two co-planar arms extending outwardly therefrom terminating in free ends, said arms being bent inwardly to form hook members, a guide eye attached to the support arm comprising a base portion and a thread receiving portion, a cylindrically shaped recess longitudinally of the base portion forming a seat for the free end of the arm and a plurality of diametrically opposite grooves in the body portion of the guide to receive the arms of the loop, each groove terminating in a recess at its end near the thread receiving portion of the guide to receive the hook members formed in the ends of the loop.

MICHAEL J. McHALE.
